UNITED STATES PATENT OFFICE.

RAYMOND D'EQUEVILLEY-MONTJUSTIN, OF KIEL, GERMANY.

ENTRANCE-SHAFT FOR SUBMARINE BOATS.

932,379.

Specification of Letters Patent. Patented Aug. 24, 1909.

Application filed April 6, 1908. Serial No. 425,461.

To all whom it may concern:

Be it known that I, RAYMOND D'EQUEVILLEY-MONTJUSTIN, a subject of the King of Spain, and a resident of Kiel, in the Empire of Germany, have invented certain new and useful Improvements in Entrance-Shafts for Submarine Boats, of which the following is a specification.

The present invention relates to the type 10 of entrance-shafts for submarine boats in which the upper and lower ends of the shaft are provided with hinged doors or flaps for closing the shaft.

The object of the invention is to improve 15 this type of shafts in such a manner that, in case the flaps are inadvertently left open, the lower flap will be closed by the water entering the shaft when the boat dives or when heavy seas break over the deck.

20 In the accompanying drawings, Figure 1 shows a side view, partly in section, of a submarine boat provided with the improved entrance-shaft, the flaps of the shaft being closed; Fig. 2 is a sectional view, on an enlarged scale, of a part of Fig. 1, the flaps being open, and Fig. 3 is a perspective view of a detail.

The entrance-shaft A leads to the compartment B for the crew in the manner 30 shown in Figs. 1 and 2. The shaft is inclined and is of rectangular cross-section. At the upper and lower ends of the shaft are provided hinged doors or flaps C, D, for closing the shaft. When the upper flap C is 35 closed, the flap overlaps the upper end of the shaft A. The lower flap D has a central countersunk portion d¹ which can engage in a corresponding opening a¹ in the lower end wall of the shaft. To the flap D are secured 40 two sheet-metal plates d² which lie against the side walls of the shaft. These plates serve to limit the opening movement of the flap D (Fig. 2) and guide the flap along the side walls of the shaft in such a manner that 45 water cannot enter between the plates and the side walls of the shaft. The weight of the flap D and its position in opened condition are selected in such a manner that the flap automatically closes when the space between the wall a² of the shaft and the opened 50 flap D becomes filled with water. In their closed condition, the flaps C and D may be bolted to the shaft by suitable securing means (not shown in the drawing). The

flap D and the wall a² of the shaft are provided with ribs d³ and a³ which serve as steps for the crew entering or leaving the compartment.

If the flaps C D are inadvertently left open and water enters the shaft, due to the boat 60 diving or due to heavy seas breaking over the boat, the inclined position of the shaft A causes the water to flow along the wall a² and pass behind the flap D, the weight of the water and the shock effected thereby 65 causing the flap to close. In the shaft according to the present invention, when water enters the shaft, the lower flap is therefore more certain to close than is the case 70 with vertical shafts.

Having thus described the invention, what is claimed and desired to be secured by Letters Patent is:—

1. The combination with an entrance shaft for submarine boats having an inclined 75 wall along which water entering the shaft is adapted to pass, of means swingingly mounted adjacent to the lower end of said wall and adapted to receive the impact of the water to automatically close the shaft. 80

2. An inclined entrance shaft for submarine boats having means at its upper end for closing the shaft, and having means at its lower end for closing the shaft; said last-named means being adapted to receive the 85 impact of water entering the shaft to automatically close the lower end of the shaft.

3. An inclined entrance shaft for submarine boats having a closing member hinged to the upper end of the shaft, and a closing 90 member hinged at the lower end of the shaft, said last-named member being adapted to receive the impact of water entering the shaft to automatically close the lower end of the shaft. 95

4. An inclined entrance shaft for submarine boats having a closing flap at its upper end, a closing flap at its lower end, and means for supporting said last-named flap when opened in position to receive the impact of 100 water entering the shaft to cause the water to close the flap.

The foregoing specification signed at Kiel, Germany, this 9th day of March, 1908.

RAYMOND D'EQUEVILLEY-MONTJUSTIN.

In presence of—

JULIUS RÖPKE,

FERDINAND ROHWEDDER.
